UNITED STATES PATENT OFFICE.

EDWIN H. POWELL AND ALBERT R. HOMER, OF CLEVELAND HEIGHTS, OHIO.

ATTACHMENT FOR REFLECTORS.

Application filed September 22, 1921. Serial No. 502,440.

To all whom it may concern:

Be it known that we, EDWIN H. POWELL and ALBERT R. HOMER, citizens of the United States, and residents of Cleveland Heights, in the county of Cuyahoga and State of Ohio, have invented a certain new and useful Improvement in an Attachment for Reflectors, of which the following is a full, clear, and exact description.

10 The present invention relates to a device which is intended and adapted to be used in connection with a reflector, more particularly of the type which is at present in common use with headlights for automobiles and 15 similar vehicles.

The object of the invention is to provide a construction which will prevent a glare from the light with which the device is associated and at the same time will in conjunction with the reflector proper cause a beam of light to be projected in front of the headlight, but at such a height from the ground that persons standing in front of or approaching the headlight will not observe that brilliancy from the light which is usually known as a glare.

Reference should be had to the accompanying drawings forming a part of this specification in which Fig. 1 is a front elevation of the device attached to a reflector of usual form for headlights; Fig. 2 is a sectional elevation; Fig. 3 is a bottom plan view of the device and Fig. 4 is a perspective view.

35 In the present drawing and specification, the usual casing for a headlight which carries the reflector proper, is omitted inasmuch as this construction is very well known and forms no part of the present invention.

40 Referring to the drawings, 1 indicates a reflector of usual construction which as is well known has, substantially, the surface of a paraboloid. At the center portion of the reflector there is an opening which receives a lamp socket 2 in which socket is placed a small electric bulb 3. The outer edge of the reflector proper is formed with the outwardly extending flange 4 which on the one surface thereof cooperates with the 45 glass front or lens 5 of the headlight and the other surface of the flange 4 rests against the forward edge of the casing, the reflector and glass being secured in the casing of the lamp by means of a head or cap which has 50 suitable attachment to the casing. The con-

struction referred to being old is not shown in the drawings.

The device of the present invention comprises a body which is formed preferably of sheet metal and the body is formed to have 60 an annular flange portion 6 of substantially uniform width and is formed to fit against the upper portion of the surface of the reflector 1, in other words the outside surface of the flange 6 is a portion of a parabolic 65 surface when the reflector such as 1 with which it cooperates is a parabolic reflector.

At the inner edge of the flange 6, and preferably, as before stated, formed integrally is a portion 7 having a rounding 70 inner and outer surface and when the device is assembled with respect to the reflector the inner surface of the part 7 is oppositely disposed with respect to a portion of the upper surface of the reflector 1 and this 75 portion 7 extends around and in front of the electric bulb 3 so that there is substantially no direct light from the bulb 3 which can pass beyond the portion 7. The line on which the edge of this curved portion 7 80 meets with the surface of the reflector proper is substantially a semi-circle.

The curvature given to the inner surface of the portion 7 is such that when the device is associated with a reflector such as 1 85 in the manner indicated in Figs. 1 and 2, that portion of the light which is reflected by the reflector 1 against the surface of the portion 7 will be again reflected against the reflector 1 with the result that the rays of 90 light projected from the headlight will be directed downwardly below a line coincident with the axis of the reflector 1, thereby eliminating all glare but at the same time the intensity of light will not be appreciably diminished nor will the projection of the light in front of the headlight be materially diminished over what would be the case if the device of the present invention were omitted.

100 For the purpose of obtaining better reflecting effects the inner surface of the portion 7 is silvered or otherwise made highly reflecting in the same manner as is customary with reflectors.

105 For the purpose of retaining the device within the reflector 1, extending clips 8 are provided, having bent over portions 8^a, and these bent over portions are adapted to be bent around the flange 4 of the reflector 1. 110

When the glass or lens 5 is positioned and held in position by the removable head of the headlight, the glass will be firmly pressed against the tangs 8 and thus hold them 5 against any movement.

The flange 6 is provided with an opening 9 which is adapted to permit passage of the socket for a dimmer lamp 10 where the same is used.

10 It has been found very desirable to provide the inner surface of the flange 6 and the outer surface of the portions 7 with a polished or silvered surface because as is obvious some light from the lower portion 15 of the headlight will enter the upper portion thereof outside the light obstructing member. This is not a great quantity of light but by providing a polished surface for reflecting the same, it projects a soft- 20 ened dimmer light so that the upper part of the headlight is not dark but is partly illuminated.

Additionally, where a dimmer lamp is used, by polishing or silvering the inner surface of the flange 6 and outer surface of the 25 portion 7, a reflecting surface is formed which cooperates with the dimmer lamp.

As before stated, the device is preferably made of a stamping of light sheet metal, thus being possible of production at a low 30 cost and it serves to effectively prevent the glare of head lamps without any appreciable diminution of the light projected by the head light.

Having described our invention, we claim: 35

The combination with a reflector having a curved surface and provided with an outer rim and a lamp centrally disposed therein, of a member having a flange portion which engages with a portion of the surface of the reflector and clips formed by spaced hook shaped tongues integral with the flange, said clips projecting outwardly from the outer edge of the flange and adapted to engage with the rim of the reflector to detachably 40 secure said member thereto, said member also having a portion with a curved surface which extends transversely between opposite wall portions of the reflector and in front of said lamp. 45

In testimony whereof, we hereunto affix our signatures.

EDWIN H. POWELL.
ALBERT R. HOMER.
